(57) **CLAIM**

The ornamental design for a combined razor handle, cartridge, and package, as shown and described.

DESCRIPTION

FIG. 1 is a perspective view of a combined razor handle, cartridge, and package of the present invention;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines illustrate portions of the combined razor handle, cartridge, and package and form no part of the claimed design.

1 Claim, 5 Drawing Sheets
